UNITED STATES PATENT OFFICE

142,221

DESIGN FOR AN EYE SHIELD FRONT

William C. Moeller, Kansas City, Mo., assignor to
A. F. Parmalee, doing business as United States
Safety Service Co., Kansas City, Mo.

Application January 22, 1945, Serial No. 117,551

Term of patent 14 years

(Cl. D57—1)

To all whom it may concern:

Be it known that I, William C. Moeller, a citizen of the United States, residing at Kansas City, in the county of Jackson and State of Missouri, have invented a new, original, and ornamental Design for an Eye Shield Front, of which the following is a specification, reference being had to the accompanying drawing, forming a part thereof.

Fig. 1 is a front elevational view of the eye shield front, showing my new design.

Fig. 2 is a top plan view thereof; and

Fig. 3 is an end elevational view thereof.

The eye shield front is made of a single, molded piece of transparent material, having a front panel arched both longitudinally and transversely. The continuous flange is arched in two directions and the zone of juncture between the front panel and flange is arched to merge these elements without establishing a restricting area for the lines of vision.

I claim:

The ornamental design for an eye shield front, as shown and described.

WILLIAM C. MOELLER.
